UNITED STATES PATENT OFFICE.

JOHN G. BRECKENRIDGE, OF SPRINGFIELD, OHIO, ASSIGNOR TO THE RIDGELY TRIMMER COMPANY, OF SPRINGFIELD, OHIO, A CORPORATION OF WEST VIRGINIA.

PAPER-TRIMMER.

No. 908,540.

Specification of Letters Patent.

Patented Jan. 5, 1909.

Application filed May 23, 1907. Serial No. 375,216.

To all whom it may concern:

Be it known that I, JOHN G. BRECKENRIDGE, a citizen of the United States, residing at Springfield, in the county of Clark and State of Ohio, have invented certain new and useful Improvements in Paper-Trimmers, of which the following is a specification.

My invention relates to paper trimmers. 10 It is particularly adapted to the combination of a paper cutter with a straight-edge generally used therewith, and my object is to construct the device so that the connection between the paper trimmer and 15 the straight edge will be improved. It is customary to use the paper cutter with the straight edge placed horizontally and also with the straight edge placed vertically, and my improved device is one that is adapted 20 to insure a more satisfactory operation when the paper cutter is subjected to these different uses.

Referring to the accompanying drawings, 25 Figure 1 is a side view of the paper trimmer in position on the straight edge. Fig. 2 is a view taken from the opposite side from that shown in Fig. 1. Fig. 3 is an end view looking toward the right in Fig. 1. Fig. 4 is a detail view of the part known as 30 the gage. Fig. 5 is a detail view of the anti-friction roller.

Like letters of reference indicate like parts throughout the several views.

In the drawings, the straight-edge is indicated by a . It is formed with the usual groove or guide, a^1 . (See Figs. 2 and 3.) The gage, a^2 , is formed with the usual bearings, a^3 , which project outwardly and engage in the groove, a^1 formed in the straight 40 edge, and the trimmer is held against tipping movement by reason of this engagement. The casing or head, a^4 , is formed with a hub like portion, a^5 , and the arbor for the disk or blade, a^{12} , is supported within this portion in the usual manner, as clearly set forth and described in Letters-Patent No. 533,375, issued to Chas. T. Ridgely. The casing, a^4 , is pivotally secured to the gage, a^2 , and the guide, a^1 , 45 (Fig. 1) is for guiding the casing, a^4 , during its up and down movement. The pivot-screw, a^6 , forms the pivotal connection between the casing and gage, and the screw, a^8 ,

constitutes the guide which extends within the groove, a^7 , for guiding the casing, as 55 hereinbefore explained. The anti-friction roller, a^9 , projects from the extension of the casing, a^4 , and this roller engages the flat upper surface of the straight edge, as indicated in Figs. 2 and 3. There is the usual 60 spring connection, a^{10} , between the casing and gage, and I have shown this spring supported on the gage, one end projecting against the surface of the gage and the other end projecting against the surface formed 65 on the casing, as shown clearly in Fig. 2.

From this construction it is apparent that when the paper cutter is placed on the straight edge, the spring, a^{10} , normally exerts its tension to force the roller, a^9 , in 70 frictional engagement with the flat surface of the straight edge, but when the operator, by exerting the pressure of the hand on the handle, a^{11} , depresses the casing, a^4 , against the tension of the spring, a^{10} , the casing will 75 have a pivotal movement on the pivot, a^6 , and thereby the roller, a^9 , will be elevated from frictional engagement with the flat surface of the straight edge, and in operation the paper cutter will be manipulated 80 free of any frictional engagement at that point. But when the operator removes his hand from the paper cutter, the roller, a^9 , will automatically engage the upper surface 85 of the straight edge, and if the straight edge is in vertical position the gravity or weight of the paper cutter will not cause it to fall off of the straight edge but the parts will remain in their proper adjusted position. 90

Having thus described my invention, I claim—

1. In a paper trimmer, the combination of a gage with a straight edge supporting same, a casing pivotally connected to the gage, a disk supported by the casing, and a projection normally engaging the straight edge and means for automatically releasing the projection from the engagement with the straight edge, substantially as specified. 95

2. In a paper trimmer, the combination of a gage with a straight edge supporting the gage, a casing yieldingly connected with the gage, and a projection engaging the straight edge and automatically released 100 therefrom by the depression of the casing. 105

3. In a paper trimmer, the combination of a straight edge, with a gage slidingly supported therein, a casing, a spring connection between the casing and the gage, an anti-friction roller normally engaging the straight edge and held in engagement thereon by the spring connection, and means for automatically releasing the anti-friction

roller from engagement by the depressing of the casing, substantially as specified. 10

In testimony whereof, I have hereunto set my hand this 21st day of May 1907.

JOHN G. BRECKENRIDGE.
